DESIGN FOR A GARDENIA MOUNT

Alex Ordens, Milwaukee, Wis.

Application August 26, 1943, Serial No. 110,999

Term of patent 14 years

(Cl. D29—1)

To all whom it may concern:

Be it known that I, Alex Ordens, a citizen of the United States, residing at Milwaukee, in the county of Milwaukee and State of Wisconsin, have invented a new, original, and ornamental Design for a Gardenia Mount, of which the following is a specification, reference being had to the accompanying drawing, forming part thereof.

In the drawing:

My design for a gardenia mount is characterized by substantially the specific configuration shown in the drawing.

I claim:

The ornamental design for a gardenia mount, as shown and described.

ALEX ORDENS.
